TENT FOR REAR-DOORED VEHICLE

Frederick W. Woodward, Dearborn Heights, Mich., assignors to Donald Thornber and B. Bernice Thornber

Filed June 12, 1972, Ser. No. 261,841

Term of patent 14 years

FIG. 3

FIG. 1 is a perspective view of a tent for rear-doored vehicle showing my new design, it being understood that the broken lines are for illustrative purposes only;

FIG. 2 is a side elevational view thereof;

FIG. 3 is an end elevational view thereof; and

FIG. 4 is a top plan view thereof.

I claim:

The ornamental design for a tent for rear-doored vehicle, as shown and described.
